(57) **CLAIM**

I claim the ornamental design for a fishing lure, as shown and described.

DESCRIPTION

FIG. 1 is an isometric front, top left side view of a fishing lure;

FIG. 2 is a right side elevation view thereof;

FIG. 3 is a left side elevation view thereof;

FIG. 4 is a rear view thereof;

FIG. 5 is a front view thereof;

FIG. 6 is a bottom view thereof; and,

FIG. 7 is a right elevation view thereof with a bottom side fish hook attached.

The broken lines depict environmental structure and are included for purposes of illustration only and form no part of the claimed design.
